FIG. 2.

INVENTOR:

Claudius Dornier.

UNITED STATES PATENT OFFICE.

CLAUDIUS DORNIER, OF FRIEDRICHSHAFEN, GERMANY, ASSIGNOR TO THE FIRM ZEPPELINWERK LINDAU GESELLSCHAFT MIT BESCHRANKTER HAFTUNG, OF LINDAU-REUTIN, GERMANY.

AEROPLANE.

Application filed August 24, 1921. Serial No. 494,977.

To all whom it may concern:

Be it known that I, CLAUDIUS DORNIER, a citizen of the German Empire, residing at Friedrichshafen, Germany, have invented 5 certain new and useful Improvements in Aeroplanes, of which the following is a specification.

My invention relates to flying machines and more especially to aeroplane, and it is 10 an object of my invention to produce flying machines of the type specified which will be able to start and land with the shortest run possible. This particular object is accomplished by means of a flying machine, the 15 propeller axis of which is, in accordance with my invention, disposed so as to possess an upward inclination relatively to the axis of the flying machine. In order to still further increase the effect hereby attained, the 20 axis of the flying machine, when this latter is resting on the ground, may be directed upwards as steeply as possible. In a preferred form of my novel flying machine the angle, at which the propeller exerts a pull 25 on the machine is variable. In accordance therewith the propeller is adapted to be oscillated about a substantially horizontal axis so as to act as a lifting propeller. Preferably the motor is suspended in such manner 30 as to be able to follow this oscillatory movement of the propeller and both the motor and the propeller are free to turn about their axis automatically whereby the propeller is enabled to adjust itself to the most 35 favorable angle. I may further provide means for limiting the oscillation and for fixing both the motor and the propeller in any desired position relatively to the flying machine proper.

40 In a machine of the kind aforesaid the proportion between the pull exerted by the propeller and the total weight of the machine is of great importance. According to the present invention this proportion is preferably so chosen that the pull is at the least equal to the total weight. In order to provide for the differences in starting a machine of this novel type, as compared with machines of the usual type, the end of the machine or the spur attached thereto, respectively, are so constructed that the machine is enabled, when starting, to turn about this point.

In the drawings affixed to this specifica-

tion and forming part thereof two modifications of a flying machine of the monoplane type embodying my invention are illustrated diagrammatically by way of example.

Referring to Fig. 1, the axis *a* of the flying machine intersects with the horizontal line *b* at the comparatively big angle $\alpha=40^\circ$. On the other hand, the axis *c* of the propeller intersects the axis *a* at the angle β . It will thus be seen that the axis *c* is disposed at a still greater incline relatively to the horizontal plane than the axis *a*. The rear end 60 of the flying machine is provided with a runner *d* of customary type having a hook shaped brake spur *e*, by means of which the tail end of the flying machine may be held 65 down on the ground when starting or landing. By means of a wire rope (not shown), the brake spur may be drawn up from the driver's seat.

In the machine illustrated in Fig. 2 the 75 hull 1 carries a motor 2 driving the traction propeller 3, which latter is free to turn or oscillate about a horizontal axis 4 so as to assume the position 3' (shown in dotted lines). The original propeller axis 5 forms 80 with the vertical axis 3' an angle α . In the position 3' the traction propeller acts as a lifting screw. As shown, the longitudinal axis of the hull encloses with the ground an angle of about 25°.

85 My invention is applicable to aeroplanes of any kind whatsoever, it is, however, preferably intended for monoplanes since it affords special advantages in connection with machines of this particular type.

I claim:

1. An aeroplane comprising a hull, landing gear fixed to said hull in such position, that the longitudinal axis of the hull when the machine is resting on the ground is inclined to the ground and a propeller shaft normally mounted in said hull at a greater angle to the ground than the longitudinal axis of said hull.

100 2. An aeroplane comprising a hull, landing gear fixed to said hull in such position, that the longitudinal axis of the hull when the machine is resting on the ground, is inclined to the ground, a propeller shaft normally mounted in said hull at a greater angle to the ground than the longitudinal axis of said hull and a propeller on said shaft capable of exerting a pull which is at

least equal to the weight of the aeroplane.

3. An aeroplane comprising a hull, landing gear fixed to said hull in such position, that the longitudinal axis of the hull when the machine is resting on the ground is inclined to the ground and a propeller shaft normally mounted in said hull at a greater angle to the ground than the longitudinal axis of said hull and capable of being adjusted in said hull at a still greater angle.

4. An aeroplane comprising a hull, landing gear fixed to said hull in such position, that the longitudinal axis of the hull when the machine is resting on the ground, is inclined to the ground, a propeller shaft normally mounted in said hull at a greater angle to the ground than the longitudinal axis of said hull and capable of being adjusted in said hull at a still greater angle and a propeller on said shaft capable of exerting a pull which is at least equal to the weight of the aeroplane.

5. An aeroplane comprising a hull, landing gear fixed to said hull in such position, that the longitudinal axis of the hull when the machine is resting on the ground, is inclined to the ground at an angle of 25° to 40° and a propeller shaft normally mounted in said hull at a greater angle to the ground than the longitudinal axis of said hull.

6. An aeroplane comprising a hull, landing gear fixed to said hull in such position, that the longitudinal axis of the hull when

the machine is resting on the ground, is inclined to the ground at an angle of 25° to 35°, a propeller shaft normally mounted in said hull at a greater angle to the ground than the longitudinal axis of said hull and a propeller on said shaft capable of exerting a pull which is at least equal to the weight 40 of the aeroplane.

7. An aeroplane comprising a hull, landing gear fixed to said hull in such position, that the longitudinal axis of the hull when the machine is resting on the ground is inclined to the ground at an angle of 25° to 40° and a propeller shaft normally mounted in said hull at a greater angle to the ground than the longitudinal axis of said hull and capable of being adjusted in said hull at a 50 still greater angle.

8. An aeroplane comprising a hull, landing gear fixed to said hull in such position, that the longitudinal axis of the hull when the machine is resting on the ground, is inclined to the ground at an angle of 25° to 40°, a propeller shaft normally mounted in said hull at a greater angle to the ground than the longitudinal axis of said hull and capable of being adjusted in said hull at a 60 still greater angle and a propeller on said shaft capable of exerting a pull which is at least equal to the weight of the aeroplane.

In testimony whereof I affix my signature.

CLAUDIUS DORNIER.
